United States Patent Office.

WILLIAM DAMEREL, OF BROOKLYN, NEW YORK.

Letters Patent No. 77,963, dated May 19, 1868.

IMPROVEMENT IN UMBRELLAS.

The Schedule referred to in these Letters Patent and making part of the same.

TO ALL WHOM IT MAY CONCERN:

Be it known that I, WILLIAM DAMEREL, of Brooklyn, in the county of Kings, in the State of New York, have invented a new and useful Improvement in Umbrellas and Parasols; and I do hereby declare the following to be a full, clear, and exact description thereof, which will enable those skilled in the art to make and use the same, reference being had to the accompanying drawing forming part of this specification, in which drawing—

Figure 1 is an elevation of an umbrella extended, the runner being held up by a spring-hook.

Figure 2 represents the umbrella in red outline, the spring-hook being provided with a stop, according to my application filed December 17, 1866, said stop serving to limit the upward movement of the runner, and also to retain the spring-hook in line with the stick. The runner may be arrested by a stop on the stick, if preferred.

Figure 3 shows the umbrella as it appears when the spring-hook has been pushed outwards from the stick to allow the runner to descend and the umbrella to be closed.

Figure 4 is a cross-section of the stick in the line xx , fig. 1.

Figure 5 is a cross-section of a stick made of a single tube.

Figure 6 shows a modification, in which the stick is made from semi-cylinders.

Figure 7 shows a double tube without a rib.

Figure 8 illustrates a method of making the umbrella-stick of double tubes.

Similar letters indicate corresponding parts.

The letter a designates the stick or handle of an umbrella: b is the crown-piece, and c the runner, both of which are in this example free to turn on the stick, although my improvement can be used on umbrellas and parasols which have the crown-piece immovably fastened to the stick. The said crown-piece b is not allowed to move up or down, being placed between collars or pins, which allow it to turn, but not to slide on the stick. d is a spring-hook, which extends downwards from the crown-piece at a proper distance from the stick to engage the flange of the runner, and hold the latter up when it is desired to keep the umbrella extended.

The shank of the hook may be provided with a stop to limit the upward movement of the runner, and to keep the spring-hook in line with the stick, as is set forth in my application filed December 17, 1866, but I do not lay claim to the stop in this application, and therefore no further description or explanation thereof is necessary.

On the shank of the spring-hook, below the point which is occupied by such, a stop I form a swell or cam, e , from which the shank recedes both above and below.

The object of this device is to enable the spring-hook to be automatically sprung away from the stick when the runner is to be released, and the umbrella closed. The runner is elongated above the flange to which the stretchers are hinged, and to the upper end of the elongation is attached a collar, f , which is held to the body of the runner by means of rigid arms, h , that pass loosely through the upper flange, g , of the runner, and are bent into hooks beneath said flange, so as to hold the collar to the runner, and yet allow it to become separated therefrom at times the length of the arms.

The flange g is so formed that its under side forms an acute angle with the exterior of the runner, to enable it to be engaged with certainty by the spring-hook d , when the umbrella is to be held open, while its upper side forms an obtuse angle with the stick, or, in other words, is bevelled downwards to enable the said flange to pass the hook when the runner is shoved upwards on opening the umbrella. The under side of the hook is also bevelled, but in the reverse direction.

The sliding collar, f , is in form a horizontal section of an inverted cone, and, as it is always in advance of the runner, it comes first in contact with the under side of the spring-hook, when the umbrella is opened, and easily passes it, owing to the bevelled form of the bottom of the hook.

The operation of opening and closing the umbrella is as follows:

When the umbrella is to be raised, the runner is pushed upwards until its flange g has passed the bottom

of the spring-hook, when the operator releases the runner, and allows it to hang upon the hook, which holds it up, and thereby keeps the umbrella open as long as is desired. When the umbrella is to be closed, it is not necessary for the operator to seize the hook and withdraw it from engagement with the runner, but its disengagement is accomplished automatically, by means of the runner itself, in the following manner: The runner is pushed still further upwards, until the collar f strikes the swell or cam e of the spring-hook, and springs the hook outwards far enough to free it from the runner.

The collar is held stationary between the shank of the hook and the stick by friction, and to insure its retention until positive force is used to pull it down. I have made the shank of the hook to recede above the cam, so as to allow the upper edge of the collar to be caught by the cam, the collar being at the same time prevented from being pushed too far upwards by means of a stop, as before explained. So long as the collar is thus held, the hook remains disengaged from the runner, which is then drawn downwards past the bottom of the hook, and so soon as it has moved downwards a distance equal to the length of the hooked arms h , which attach it to the collar, the latter is immediately pulled downwards and released from its confinement between the stick and the shank of hook d , and it continues to follow the runner, its conical sides enabling it to pass the point of the hook with facility and certainty, and it again takes its place next the runner, its arms extending along the elongated upper part hereof.

By means of this part of my invention, therefore, I am enabled to close the umbrella automatically, the spring-hook being operated by the runner itself, the hook itself being shortened, so that the flange of the runner, which holds the stretchers, does not rise as high as the bottom of the hook, and therefore does not interfere with it, as in those umbrellas where pendent hooks or detents are made of such a length as to pass down between the stretchers in order that the operator may reach its end and push it away from the runner.

My invention relates, further, to the construction of sticks for umbrellas and parasols.

The stick, a , is formed of double tubes, placed one within the other. Within the inner tube, throughout the length of the stick, is fixed a bridge-piece or rib, i , that extends across it in the line of its diameter, one edge being held fast in the seam or joint of the tube, and the other resting against the opposite side of the tube.

The object of the rib is to stiffen the stick. It also facilitates the closing of the seam or joint of the tube, by soldering or brazing where the tube is made of very thin material, an angle being formed on each side of the rib, along the whole length of the seam or joint, which enables the soldering-material, when the tube is immersed therein, to adhere more readily than it would to a plain seam or joint.

I employ the said rib in sticks made of single tubes as well as in those made of double tubes, an example of the former kind being shown in fig. 5.

The outer and inner tubes are placed together, either before or after the rib i is soldered or brazed to the inner, as may be preferred.

In order to enable those skilled in the art to make sticks of double tubes according to my invention, I give the following explanation:

Before placing the said tubes together, I clean them of grease and other foreign substances by means of muriatic or other suitable acids, and wet them with a solution of sal-ammonia, and then insert the smaller within the larger, in such a manner as to break joints; that is to say, their seams or joints come opposite the solid portions of the tubes respectively. The double tubes are in the next place passed through a series of rollers and guides like that represented in red outline in fig. 8, for the purpose of connecting them together, and at the same time closing the seam or joint of the outer tube, using in the operation a sufficient degree of heat to effect a union or cementation between the surfaces of the tubes which are in contact.

The rollers are grooved to the depth of half the diameter of the double tube, so that they will act as feed-rollers, whilst they also compress the sides of the outer tube, and force them against the inner, and close the edges of the outer tubes, thereby bringing the parts into proper relations to each other for effecting a complete union of the tubes by cementation, under the influence of heat, in conjunction with the sal-ammonia solution, acting as a flux. The rollers revolve so as to carry the tube slowly towards the right. After passing the first pair of rollers, the tubes go between guides, which support them, and keep the outer tube closed upon the inner, so as to present them in proper relations to the flame of a lamp or furnace placed behind the first set of guides. The heat of the flame, in conjunction with the flux or cementing-material, unites or solders the adjacent surfaces of said tubes together, and the two tubes become, in effect, a single tube, possessing the united strength of the two.

After passing the lamp or furnace, they go through or between guides, which have tubular elongations, that keep the sides of the tubes compressed, so as to give them time to cool and allow the fused metal or solder to set firmly. From thence they go between a second pair of grooved feeding-rollers, which carry the tube out of the apparatus.

I do not, in this application, lay claim to the apparatus shown in fig. 8, as it properly forms the subject of a separate application, and therefore it is not necessary to give any further explanation than I have here given of the mode of making umbrella or parasol-sticks of double or compound tubes.

I make the inner tube of ordinary tin plate, and the outer tube of thin sheet brass, or other ornamental metal, to which latter the tin adheres when the two tubes are treated as described in presence of a suitable flux, or both tubes may be made of tin-plate. The tubes which I use are bent up from strips of sheet metal in the ordinary way.

In fig. 4, I have shown in cross-section a stick with double tubes, and a bridge or rib within the inner tube.

In fig. 7, I have shown a double tube, the rib being left out, so that the tube can be used for umbrellas or parasols which are made with spring-catches working in slots in the sticks. Sticks with ribs in them are more

especially applicable to umbrellas or parasols whose detents or catches are arranged as herein shown on the exterior, without requiring slots in the sticks.

The stick shown in fig. 5 has a stiffening-rib applied to a single tube, and in fig. 6 I have shown a modification, where both the inner and the outer tubes are made of semi-cylinders, cemented or soldered together edge to edge, with a rib extending through the interior, the edges of said rib being allowed to come out flush with the exterior of the inner tube, to which it is soldered before the parts which compose the outer tube are added. The tube is plugged or capped in the ordinary manner for use in umbrellas or parasols.

What I claim as new, and desire to secure by Letters Patent, is—

1. The conical collar *f*, connected to the runner *c* by means of links *h*, substantially as and for the purpose set forth.
2. The cam *e* on the spring-hook *d*, arranged to operate with the collar *f*, substantially as described.
3. An umbrella-stick, made of an inner and outer tube united throughout their length, substantially as described.
4. The bridge-piece *i*, applied within a tubular umbrella or parasol-stick, substantially as described.

This specification signed by me, this 10th day of June, 1867.

WILLIAM DAMEREL.
